STORAGE BATTERY FOR MINER'S LAMPS

Homer A. Lozeau, Worcester, Mass., assignor to Koehler Manufacturing Company, Marlboro, Mass., a corporation of Massachusetts

Filed May 11, 1964, Ser. No. 79,929

Term of patent 14 years

(Cl. D48—24)

Fig. 1.

Fig. 2.

Fig. 3.

The side and end not shown, are substantially the same in appearance as the side and end, respectively, shown, except as indicated.

I claim:

The ornamental design for a storage battery for miner's lamps, substantially as shown and described.
